HOIST PUSH BUTTON CONTROL

Robert H. Madding, Little Rock, Ark., assignor to Eaton
Yale & Towne Inc., Cleveland, Ohio, a corporation of
Ohio

Filed Mar. 10, 1966, Ser. No. 1,400

Term of patent 14 years

(Cl. D26—13)

FIG. 1

FIG. 3

FIG. 5

FIG. 4

FIG. 2

FIG. 1 is a perspective view of a hoist push button control showing my new design.

FIG. 2 is an end view showing my new design as seen from the right of FIG. 1.

FIG. 3 shows a front view as seen from the left of FIG. 2.

FIG. 4 is a plan view as seen from the bottom of FIG. 2.

FIG. 5 is a top plan view as seen from the upper side of FIG. 2.

I claim:

The ornamental design for a hoist push button control, substantially as shown.
